UNITED STATES PATENT OFFICE.

FREDERIC LLOYD, OF LEWISTON, MAINE, ASSIGNOR TO BATES MANUFACTURING COMPANY, OF LEWISTON, MAINE, A CORPORATION OF MAINE.

DESIGN FOR A QUILT.

54,426.

Specification for Design.

Patented Feb. 10, 1920.

Application filed July 15, 1919. Serial No. 311,097. Term of patent 14 years.

To all whom it may concern:

Be it known that I, FREDERIC LLOYD, a subject of the King of England, residing at Lewiston, county of Androscoggin, State of Maine, have invented a new, original, and ornamental Design for Quilts, of which the following is a specification, reference being had to the accompanying drawing, forming a part thereof.

Referring to the drawing I have shown therein a plan view of a portion of a quilt embodying my new design.

What I claim is:—

The ornamental design for a quilt as shown.

FREDERIC LLOYD.
